LAMMERT ELENGA

UNITED STATES PATENT OFFICE.

LAMMERT ELENGA, OF STERLING, NEBRASKA.

WINDOW-FRAME.

1,382,348.

Specification of Letters Patent. Patented June 21, 1921.

Application filed March 14, 1919. Serial No. 282,675.

To all whom it may concern:

Be it known that I, LAMMERT ELENGA, a citizen of the United States, residing at Sterling, in the county of Johnson and State 5 of Nebraska, have invented certain new and useful Improvements in Window-Frames, of which the following is a specification,

This invention relates to windows and window frames and more particularly to 10 that class adapted to be used for sleeping porches. The primary object of the invention is to provide a mounting for a window sash, by use of which ordinary windows of sleeping rooms may be readily converted to 15 those of a sleeping-porch type. Other objects include the provision of a window sash which will utilize all of the space within the window frame, for the admission of air and which may be readily lowered or raised. 20 Another object of the invention is to provide a disappearing sash. A further object is to provide a device of this class which may be installed while building houses of a conventional type, without altering the architect's original plans. 25

In the drawing, Figure 1, is a vertical transverse section showing the device mounted in the side wall of a building, the window sash being in a raised position. 30 Fig. 2 is a similar view to that shown in Fig. 1, the sash being lowered. Figs. 3, 4, 5, 6, 7 and 8 are detail views on an enlarged scale. Fig. 3 shows a window-sill in transverse section to clearly show a guide, the 35 slideable auxiliary sill and sash being removed. Fig. 4 is a plan view of a guide. Fig. 5 is an end view of the slideable auxiliary sill. Fig. 6 is a plan view of the same, a part being broken away. Fig. 7 is a plan 40 view showing a sash-cap, a side casing strip being shown in section. Fig. 8 is a section through a recess and guide on line 8-8 of Fig. 3.

Referring now to the drawing, in which 45 like characters indicate like parts, the invention is illustrated in connection with the upright side strips 8, the horizontal top strip 9, the sill 10, the sub sill 11 and the drip sill 12 of a window frame, the apron 50 for supporting the window sill 10 being indicated at 13, the parts mentioned for the rectangular window frame being connected in the usual manner. Numeral 14 indicates a window-screen mounted 55 upon the outside of the window frame, which may be employed, if desired. Nu-

meral 15 indicates a single upright window sash adapted to be moved in the groove 16 of the side strips 8 of the window frame, said drip-sill being disposed outwardly of 60 and adjacent to the sills 10 and 11 and the side-strips and grooves being of adequate length so that the sash may be moved vertically between the drip sill and said sills, 10 and 11 and that when the sash is lowered, 65 its upper end will be disposed between and approximately in line with the sills 10 and 12, at which time it will be seen that all of the operating parts of the invention, together with the sash, will not be visible. 70

In order that the window sash may be conveniently secured in its uppermost position and that other objects hereinafter to be described, may be attained, I provide a pair of metallic casings or guides 17, each 75 being adapted to be disposed in a suitable recess x , best shown in Fig. 8, said recesses x being formed in the side strips 8 to open upon the grooves 16 adjacent to the ends of the window sill 10, said guides being secured to the strips 8 by suitable keepers 18 engaging in flanges a and b of the guides. Numerals 19, indicate recesses formed in the sides of the guides to permit a free vertical movement of the sash, said casing or guides 80 17 adjacent to said recesses 19 being provided with flanges c adapted to be secured within the groove 16 by means of suitable keepers 20; and, as clearly shown, each guide is provided at or near one of its ends 85 with a slot s .

Numeral 21 indicates an auxiliary sill adapted to engage in the guides 17 and to be disposed horizontally upon the upper inclined surface of the drip-sill 12 and upon 90 the inclined surface d of the window sill 10, and is adapted to have transverse slideable movements thereon, a handle 22 being shown for use when manually moving it.

By referring to Figs. 1, 2 and 6 it will be 100 seen that the lower side of the auxiliary sill is rectilinear, and that its upper side is formed with a projection e intermediate its faces f and g , said faces being disposed in non-alinement. Numeral 23 indicates a metallic jacket adapted to cover the face g and the outer edge of the auxiliary sill, this being desirable since, at times, this part of the sill may be exposed to the weather.

The ends of the auxiliary sill 21 are provided with extensions h , best shown in Fig. 6, the metallic jacket 23 covering the ends 110

of said extensions as well as its top surface and outer edge, and caps 24 are employed for covering the remaining part of each end of the auxiliary sill, lugs 25 being employed 5 and each projecting outwardly from a cap 24; and when the auxiliary sill is disposed upon its support, above mentioned, its ends will engage in the metallic guides 17, its lugs 25 engaging in the slots *s* of the guides.

10 Numeral 26 indicates a horizontal closure-cap or hood which is secured to the top of the sash 15, said cap being provided in its lower side with a recess *m*. It will be understood that the window may be completely 15 elevated, and the auxiliary sill 21 may then be moved outwardly for supporting the sash as shown in Fig. 1, the lugs 25 moving in the slots *s*, the metallic jacket *g* being in engagement with the bottom of the sash and 20 projecting outwardly thereof, said sill 21 operating as a closure for the opening between the sills 11 and 12. Also the window sash may be disposed as shown in Fig. 2, the auxiliary sill 21 being drawn inwardly 25 to permit this movement of the sash, the hood or cap 26 covering the parts mentioned and the projection *e* engaging in the recess *m*, said hood operating approximately to cover and exclude the parts mentioned from 30 view, and providing a finished appearance, and in a measure, operating to exclude dust.

Numeral 27 indicates a weather-strip which is provided for the drip-sill 12, tending to prevent rain from entering the space 35 between the sills, and as best shown in Fig. 1, said strip is adapted to engage the jacket 23 of the auxiliary, slideable sill 21 when the latter is in engagement with both of the sills 10 and 12.

40 Since the slots *s* are of curved form the auxiliary sill may be moved readily and may have a swinging movement transversely when moved outwardly to the position shown in Fig. 1 for engaging the drip-sill, 45 or when moved inwardly of the window frame to the position shown in Fig. 2.

Numeral 28 (Fig. 7) indicates recesses

formed in the ends of the hood 26 to correspond with similar recesses (not shown) usually provided for the window sash for 50 receiving the sash-cords for window-weights.

While I have shown and described one construction in detail, I do not wish to be understood as limiting myself in this respect, and changes in form, size, proportion 55 and material employed may be made, without departing from the spirit of the invention, the scope of which is determined by the appended claims.

What I claim as my invention and desire 60 to secure by Letters Patent is:—

In a window construction, a frame provided with a window opening therein, a sash vertically movable in the frame, a main sill at the bottom of the frame, a drip sill at 65 the bottom of the frame and spaced from the main sill to provide between the main and drip sills a passage for the sash when lowered out of the frame, a cap piece secured to the upper end of the sash and extending from opposite sides thereof to overlap said main and drip sills and close said passage when the sash is lowered and to provide a smooth surface over the lowered sash, and a shiftable auxiliary sill adapted 70 to be advanced beneath the sash when raised to support the sash and close the passage between said sills, and adapted to be withdrawn from beneath the sash to admit the lowering of the same, said cap piece and 75 said auxiliary sill having interlocking faces adapted for engagement with one another when the auxiliary sill is withdrawn to retain the sill from displacement, said auxiliary sill being adapted to close the space 80 between the main sill and the cap piece when interpositioned between the same and when the sash is fully lowered.

In testimony whereof, I have affixed my signature in presence of two witnesses.

LAMMERT ELENGA.
